US00D749392S

(12) **United States Design Patent**
Salojärvi et al.

(10) **Patent No.:** **US D749,392 S**
(45) **Date of Patent:** **** Feb. 16, 2016**

(54) **FOLDING KNIFE**

(71) Applicant: **Fiskars Garden Oy Ab**, Billnäs (FI)

(72) Inventors: **Jouni Salojärvi**, Helsinki (FI); **Mika Sokka**, Tuusula (FI); **Petteri Masalin**, Helsinki (FI); **Heli Säde**, Billnäs (FI)

(73) Assignee: **Fiskars Garden Oy Ab**, Billnäs (FI)

(**) Term: **14 Years**

(21) Appl. No.: **29/511,220**

(22) Filed: **Dec. 8, 2014**

(30) **Foreign Application Priority Data**

Jun. 18, 2014 (EM) 002484923-0006

(51) **LOC (10) Cl.** **08-03**

(52) **U.S. Cl.**

USPC **D8/99**

(74) *Attorney, Agent, or Firm* — Foley & Lardner LLP

(57) **CLAIM**

We claim the ornamental design for a folding knife, as shown and described.

DESCRIPTION

FIG. 1 is a front view of the claimed design;

FIG. 2 is a rear view of the claimed design of FIG. 1;

FIG. 3 is a top perspective view of the claimed design of FIG. 1;

FIG. 4 is a top view of the claimed design of FIG. 1;

FIG. 5 is a bottom view of the claimed design of FIG. 1;

FIG. 6 is a left side view of the claimed design of FIG. 1;

FIG. 7 is a right side view of the claimed design of FIG. 1;

FIG. 8 is a top, front perspective view of the claimed design of FIG. 1; and,

FIG. 9 is a bottom, rear view of the claimed design of FIG. 1. The ornamental design which is claimed is shown in solid lines in the drawings. The broken lines in the drawings are for illustrative purposes only and form no part of the claimed design.

1 Claim, 9 Drawing Sheets
